COVERED JOINT HINGE

Joseph Soss, Roselle, N. J.

Application March 14, 1935, Serial No. 10,963

12 Claims. (Cl. 16—148)

This invention relates to what are known as covered joint hinges and particularly to hinges of this type designed for use in connection with motor vehicles to hingedly support the doors in connection with vehicle bodies; and the object of the invention is to provide a hinge of the character defined, the hood butt part of which is formed from two substantially similar sheet metal blanks arranged and nesting one within the other to form the complete hood butt whereby the cost of production of a butt of the class described is reduced, and at the same time, a stronger and more durable butt is provided; and with these and other objects in view, the invention consists in a hinge of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side edge view of a hinge made according to my invention.

Fig. 2 is a face view of one butt of the hinge detached.

Fig. 3 is a sectional view through the hood end of the butt shown in Fig. 2.

Fig. 4 is a section on the line 4—4 of Fig. 3.

Fig. 5 is a face view of one end portion of one of the parts of the butt shown in Fig. 2; and,

Fig. 6 is a view similar to Fig. 3 showing a slight modification.

In the art of manufacturing hinge butts of the kind under consideration, it is old to form a butt from a single piece of cast or forged metal and from machined rolled sections as well as to provide a butt consisting of a thin outer shell with a heavy or relatively thick insert. It is the purpose of my invention to eliminate the conventional methods of procedure and to construct a hinge butt from two substantially similar sheet metal parts which collectively will form a strong and durable butt of the required contour and dimensions to suit it for the intended use.

To illustrate one method of carrying my invention into effect, I have shown in Fig. 1 of the drawing a hinge consisting of two butts 6 and 7, the butt 6 having the usual attaching plate portion 8 with a curved hood portion 9 at the outer end thereof to conceal or partially conceal the joint of the hinge, the hood portion including top and bottom bearings and cover plates 10, 10a

which overlie and cover the corresponding ends of the cylindrical bearing 7a of the butt 7 which extends between adjacent surfaces of the bearings 10, 10a.

The present invention deals with the construction of the butt member 6. In practice, this butt member is composed of two parts, namely, an outer part 11 and an inner part 12, both of which are fashioned from sheet metal and which are of substantially the same general contour or may have slight structural omissions.

The outer part comprises an attaching plate portion 13 having side flanges 14, note Fig. 4, and one end of said part has a curved wall 15 forming a continuation of the plate 13 and partially forming the hood 9. The outer end portion of the curved wall 15 is also curved or bowed outwardly between the side edges of the metal strip or sheet as may be seen upon a consideration of Fig. 2 of the drawing. This butt construction adds rigidity to the hood portion of the butt and also enhances the appearance thereof. As a continuation of the upper and lower edges of the curved portion 15 as well as the side edges of the plate 13 are top and bottom cover plates 16, which partially form the plates or bearings 10, 10a. These plates include rearwardly directed extensions 17 which cover the space between the butts 6 and 7 at the outer end portion of the hinge as will appear upon a consideration of Fig. 1 of the drawing. The plates 16 are provided with apertures 18 for receiving the usual pintle pin, not shown, employed to couple the two butts 6 and 7 together.

The part 12 of the butt 6 comprises an attaching plate portion 13a slightly narrower in width than the plate portion 13 and preferably seating within the flanges 14 and of a thickness equal to the height of the flanges. In other words, the flanges are omitted from the plate portion 13a. At one end of the plate portion 13a is a curved portion 15a which is cut out in order to receive the cylindrical bearings 7a of the butt 7 and to reduce the wall thickness of the hood 9 as a whole, and especially that part thereof in which the bearing 7a operates, especially at the outer end or edge of said hood portion.

Said end of the butt part 12 or the plate 13a thereof includes side plates 16a seating and fitting snugly within the plates 16 and conforming to the peripheral contour thereof—that is to say, the plates 16a include extensions 17a similar to the extensions 17, and apertures 18a in alignment with the apertures 18. It will thus be apparent that the two cover plate portions 16, 16a will

form relatively thick pindle bearings 10, 10a on the resultant butt member and the curved hood portion 8 of said butt member as well as the attaching plate portion 8 thereof will be reinforced and strengthened by virtue of the use of the two sheet metal parts which are arranged to fit snugly one within the other and may, if desired, be pressed one within the other under pressure, and further, may be welded together 10 to prevent any possible shifting or displacement of the parts one with respect to the other. At 19 in Fig. 2 of the drawing I have indicated two welded portions.

The separate butt parts 11 and 12 will be fashioned from suitable blanks and shaped to the desired form and contour by the use of suitable dies, thus providing a low manufacturing cost of said parts including the butt as a whole when the parts are assembled. At the same time it 20 will appear that a hinge butt of strong and durable characteristics is produced. By virtue of the manner of constructing the pindle bearing portions 10, 10a, there is no possibility of the spreading or opening of such bearings which has been experienced with other types of hinges including inserts having rolled or curled pindle bearing portions.

Where the question of appearance is not an important factor, the hood end portions of the 30 two butt parts may be made identical in design and contour and arranged to fit snugly one within the other, it being understood that the cutting out of part of the curved hood portion of the inner part as shown in the accompanying 35 drawing is merely to adapt the hinge to the design and contour disclosed.

In Fig. 6 of the drawing I have shown a slight modification. In this construction, the outer part 20 and inner part 21 of the butt are of the same 40 construction throughout; in other words, these parts have hood portions 22 and 23 respectively which are continuous to the outer or free edge 24 thereof. The top and bottom walls of both 45 hood portions or parts forming the pindle bearings, one of which is shown at 25 in Fig. 6, are substantially the same as the bearings 16 shown in Fig. 2, the only difference being that the pindle aperture 26 of the bearings 25 is located inwardly a sufficient degree to provide clearance 50 for the pindle bearing of the other companion butt of the hinge to clear the hood portion 23, as will be apparent. With this construction, the 55 side flanges such as shown at 14 in Fig. 2 of the drawing for the outer butt part 20 may be omitted. With this construction, two butt parts of identical construction can be placed and forced under die pressure one within the other to form the complete hinge.

In this operation, the inner part 21 including 60 its hood portion 23 and end walls 25a will be contracted and drawn to seat in the outer part 20, 22 including the end wall portions thereof, the result of which operation will be to firmly unite the parts against separation, and protruding edges of the inner part 21 or the hood portion 23 and walls 25 thereof will be trimmed to correspond to the size and contour of the similar portions of the outer part 20 of the butt. The apertures 26 are formed after the two parts have 65 been assembled.

While welding is not essential with the construction shown in Fig. 6, the attaching plate portions 20a, 21a of the parts 20, 21 may be welded together if desired. While I have stated that 70 the two parts 20, 21 may be of identical size

and construction and assembled in the manner above defined, the inner part 21 may be made slightly smaller than the outer part or to forcibly fit within the outer part so as to insure firm engagement of adjacent walls, especially 5 throughout the hood end portion of the resultant butt.

The thickness of the sheet metal employed in the separate butt parts may be varied to suit the requirements in the wall thickness of 10 the attaching plate portions of the butts as well as the pindle bearing portions thereof. In other words, if quarter inch thicknesses are required in the resultant butt, one-eighth inch sheet metal will be employed; whereas, if three-eighth 15 inch is desired, three-sixteenth inch sheet metal will be employed, etc.

My improved hinge may be constructed from two sheet metal parts of substantially the same contour wherein one part is constructed from a 20 sheet of metal thinner than the other part, but in all such cases, the pindle bearing portions will be formed from the two sheet metal parts and bent or drawn inwardly from opposite side edges thereof by suitable dies which also form the hood 25 portions.

Hinges of the class under consideration may be economically produced by reason of the fact that all machine operations such as grinding, 30 planing and the like are eliminated. At the same time, finished surfaces are provided for receiving the companion butt of the hinge.

The more important phase of the present invention is in the provision of the reinforcement of the hood and the provision of the relatively 35 thick pindle bearings which could not be practically formed in a single pressed sheet of metal unless the workpiece were first heated, the expense of which operation would again materially increase the cost of production of the resulting 40 product. It is one of the outstanding features of my invention to produce the desired structural result in the most economical and practical manner and at the same time produce a hinge butt of added strength and utility as compared with 45 other butts of its kind.

Having fully described my invention, what I claim as new and desire to secure by Letters Patent, is:

1. A hinge butt for covered joint hinges comprising two sheet metal inner and outer parts, the outer part comprising an attaching plate, a curved extension at one end of the plate, and top and bottom walls continuous with said extension and plate, and the inner part comprising an attaching plate, a curved extension at one end of the plate, and top and bottom walls continuous with said extension and plate and conforming with the contour of and fitting snugly within the top and bottom walls of the outer part and forming relatively thick pindle bearings at the upper and lower sides of said butt. 50

2. A hinge butt for covered joint hinges comprising two sheet metal inner and outer parts, 65 the outer part comprising an attaching plate, a curved extension at one end of the plate, and top and bottom walls continuous with said extension and plate, the inner part comprising an attaching plate, a curved extension at one end 70 of the plate, and top and bottom walls continuous with said extension and plate and conforming with the contour of and fitting snugly within the top and bottom walls of the outer part and forming relatively thick pindle bearings at 75

- the upper and lower sides of said butt, the central portions of the curved extensions of the butts extending outwardly, and the top and bottom walls extending inwardly and longitudinally 5 of the attaching plates.
3. In covered joint hinges, a hinge butt composed of two sheet metal parts fitting snugly one within the other to form inner and outer parts, each of said parts comprising an attaching plate 10 and a curved extension at one end of the attaching plate, the outer surfaces of the inner part being arranged in firm engagement with the inner surfaces of the outer part when said parts are coupled together in forming said butt, and 15 the curved extension of each part comprising a curved side wall and top and bottom walls continuous with said side wall and the upper and lower edges of the attaching plate.
4. In covered joint hinges, a hinge butt composed of two sheet metal butt parts, each part 20 comprising an attaching plate, a curved extension at one end of said attaching plate, and top and bottom walls continuous with the side edges of said extension and attaching plate, and said 25 butt parts being arranged to fit snugly one within the other and secured together.
5. In covered joint hinges, a hinge butt composed of two sheet metal butt parts, each part comprising an attaching plate, a curved extension 30 at one end of said attaching plate, and top and bottom walls continuous with the side edges of said extension and attaching plate, said butt parts being arranged to fit snugly one within the other and secured together, and top and 35 bottom walls of said butt parts forming on the resulting hinge butt, pintle bearings substantially equal in thickness to the sheet metal of both butt parts combined and having apertures for receiving the pintle of the hinge.
6. In covered joint hinges, a hinge butt composed of two sheet metal butt parts, each part comprising an attaching plate, a curved extension 40 at one end of said attaching plate, and top and bottom walls continuous with the side edges of said extension and attaching plate, said butt 45 parts being arranged to fit snugly one within the other and secured together, top and bottom walls of said butt parts forming on the resulting hinge butt, pintle bearings substantially equal in thickness to the sheet metal of both 50 butt parts combined and having apertures for receiving the pintle of the hinge, and the side edges of the attaching plate of the outer butt part including flanges overlying the side edges 55 of the inner butt part.
7. In covered joint hinges, a hinge butt composed of two sheet metal butt parts, each part comprising an attaching plate, a curved extension 60 at one end of said attaching plate, and top and bottom walls continuous with the side edges of said extension and attaching plate, said butt parts being arranged to fit snugly one within the other and secured together, top and bottom walls of said butt parts forming on the resulting hinge butt, pintle bearings substantially equal in thickness to the sheet metal of both 65 butt parts combined and having apertures for receiving the pintle of the hinge, the side edges of the attaching plate of the outer butt part including flanges overlying the side edges of the inner butt part, and the curved extension of the inner butt part being shorter than the extension of the outer butt part to provide clearance 70 for the pintle bearing of the other butt of the hinge.
8. In covered joint hinges, a hinge butt composed of two sheet metal butt parts, each part comprising an attaching plate, a curved extension at one end of said attaching plate, and top and bottom walls continuous with the side edges 5 of said extension and attaching plate, said butt parts being arranged to fit snugly one within the other and secured together, top and bottom walls of said butt parts forming on the resulting hinge butt, pintle bearings substantially equal 10 in thickness to the sheet metal of both butt parts combined and having apertures for receiving the pintle of the hinge, the side edges of the attaching plate of the outer butt part including flanges overlying the side edges of the inner butt part, the curved extension of the inner butt part being shorter than the extension of the outer butt part to provide clearance 15 for the pintle bearing of the other butt of the hinge, and the top and bottom walls of both butt parts extending inwardly to overlie the edges of the attaching plate portion of the other butt of the hinge when both butts are in closed position.
9. A hinge comprising two hinge butts, one of 20 said hinge butts being composed of two parts arranged and fitting snugly one within the other, each part of said butt having at one end a curved extension including top and bottom walls continuous with and extending angularly from the upper and lower edges of said extension, and the adjacent top and bottom walls of said parts 25 collectively forming thick pintle bearings.
10. A hinge comprising two hinge butts, one of 30 said hinge butts being composed of two parts arranged and fitting snugly one within the other, each part of said butt having at one end a curved extension including top and bottom walls continuous with and extending angularly from the upper and lower edges of said extension, the 35 adjacent top and bottom walls of said parts collectively forming thick pintle bearings, and the curved extension of the outer butt part being of greater length than the extension of the inner butt part.
11. A hinge comprising two hinge butts, one of 40 said hinge butts being composed of two parts arranged and fitting snugly one within the other, each part of said butt having at one end a curved extension including top and bottom walls continuous with and extending angularly from the upper and lower edges of said extension, the 45 adjacent top and bottom walls of said parts collectively forming thick pintle bearings, the curved extension of the outer butt part being of greater length than the extension of the inner butt part, and the outer butt part including flanges extending longitudinally thereof and continuous with said top and bottom walls.
12. A hinge comprising two hinge butts, one of 50 said hinge butts being composed of two parts arranged and fitting snugly one within the other, each part of said butt having at one end a curved extension including top and bottom walls continuous with and extending angularly from the upper and lower edges of said extension, the 55 adjacent top and bottom walls of said parts collectively forming thick pintle bearings, the curved extension of the outer butt part being of greater length than the extension of the inner butt part, the outer butt part including flanges extending longitudinally thereof and continuous with said top and bottom walls, and means for securing said parts permanently together.
